(57) **CLAIM**

The ornamental design for an electrical connector as shown and described.

DESCRIPTION

FIG. 1 is a top, right, front perspective view of an electrical connector according to our design;

FIG. 2 is a bottom, left, rear perspective view thereof;

FIG. 3 is a top, right, front perspective view thereof;

FIG. 4 is an enlarged top, right, front perspective view of a portion thereof, as indicated at region FIG. 4 of FIG. 3;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The dash-dash broken line represents portions of the article that form no part of the claimed design. The dash-dot broken line represents the claim boundary and form no part of the claimed design.

1 Claim, 7 Drawing Sheets
